(57) **CLAIM**

The ornamental design for a folding knife as shown and described.

DESCRIPTION

FIG. 1 is a rear perspective view of a folding knife, showing our new design;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof;

FIG. 8 is an enlarged view showing the claimed area of FIG. 2; and,

FIG. 9 is an enlarged view showing the claimed area of FIG. 7.

The regular broken lines depict features of the folding knife that form no part of the claimed design. The dot-dash broken lines in FIG. 2 and FIG. 8 identify the boundary of the enlarged region.
